UNITED STATES PATENT OFFICE.

CHARLES O'DELL, OF BROOKLYN, NEW YORK, ASSIGNOR OF ONE-HALF TO FREDERICK T. REGER, OF BROOKLYN, NEW YORK.

SHINGLE CONSTRUCTION.

Application filed August 26, 1925. Serial No. 52,549.

REISSUED

This invention relates generally to shingles used for roofing purposes, the invention having more particular reference to a novel type of roofing shingles. The invention has for an object the provision of an improved roofing shingle of metal, composition, or the like; which may be easily and readily attached to the roof, and which will act more efficiently in preventing leaks. A further object is to provide a shingle construction which will practically make a double thickness on the roof. A still further object is to provide a shingle construction embodying a clip of new and novel design and application.

For further comprehension of the invention, and of the objects and advantages thereof, reference will be had to the following description and accompanying drawing, and to the appended claims in which the various novel features of the invention are more particularly set forth.

Fig. 1 of the drawing is a fragmentary plan view of a roof structure constructed in accordance to my invention.

Fig. 2 is a sectional view taken on the line 2—2 of Fig. 1.

Fig. 3 is a fragmentary sectional view, taken on the line 3—3 of Fig. 1.

Fig. 4 is a detail of a shingle as viewed from the back or rear showing the clip attached thereto.

Fig. 5 is an enlarged detail view of the clip, showing a portion of the shingle in dotted lines.

Fig. 6 is an enlarged sectional view taken on the line 6—6 of Fig. 5.

Fig. 7 is a detail of a shingle showing a modification.

The shingles 10 forming the roof structure are preferably diamond-shaped, and have their lower most corner turned back or folded as designated at 11 in the accompanying drawing.

Secured to the turned back or folded corner of the said shingle 10, is a clip 12 preferably of metal, and secured to the shingle in any desired manner, but preferably by tongues 13 struck from the clip and caused

to pierce the shingle and passed through a conveniently located hole or slot in the said clip 12, the said tongues 13 being then forced downward against the said clip, as shown in the accompanying drawing. The said clip 12 being bent, so as to completely

encircle the turned back or folded edge of the shingle; the front or top portion of the said clip 12 being cut at an angle 14 to coincide with the edges of the shingle to which the said clip is attached; the rear portion of the said clip 12 being allowed to extend past the shingle to which it is attached, said portion being cut at a right angle to the said bend in the said clip as designated by 15 in the accompanying drawing.

Referring in particular to Figure 4 of the accompanying drawing, the dotted lines 17 denote suitable markings to designate the relative positions of the adjacent shingles when the said shingles 10 are placed in position on the roof.

Referring in particular to Fig. 1 of the accompanying drawing; it will be understood that the said shingles are placed on the roof so as to over-lap one another as shown by the dotted lines 16, and further that the hereinbefore described clip will serve to hold the shingles adjacent, to which the said clip is attached, in place, as shown in Fig. 1 of the accompanying drawing.

Referring in particular to Figure 7 of the accompanying drawing showing a modification of my improved roofing shingle. The shingle 18 is preferably diamond shaped, having its lowermost corner turned back or folded as designated at 19 and having two apertures 20 and 21 punched therein to designate the location of the shingle nails or similar attaching device, and having suitable markings as shown by the dotted lines 23 to designate the relative positions of the adjacent shingles when the said shingles 18 are placed in position on the roof.

While I have above described the preferred form, construction, and arrangement of the several elements employed, it will be understood that the device is, nevertheless, susceptible of considerable modification therein, and I therefore reserve the privilege of resorting to all such changes as may be fairly embodied within the spirit and scope of the invention as claimed.

Having thus described my invention, what I claim as new, and desire to protect by Letters Patent of the United States is as follows:

1. In a shingle having its lowermost corner turned back, the combination in a clip having a back portion and a front portion completely encircling the edge of the said

- turned back corner, said front portion being cut at an angle to coincide with the edges of the shingle, said back portion being of greater length than the width of the shingle 5 at the said turned back corner, projecting therefor from both sides of said shingle, and said back portion having struck out tongues engageable in apertures of said front portion.
2. In a shingle having its lowermost corner turned back, the combination in a clip 10 having a back portion and a front portion completely encircling the edge of the said turned back corner, said front portion being cut at an angle to coincide with the edges of the shingle; said back portion being of greater length than the width of the shingle 15 at the said turned back corner, projecting therefor from both sides of said shingle, and said back portion having struck out tongues 20 engageable in apertures of said front portion, and of sufficient length to be forced downward against the said clip.
3. In a shingle of the class described, the combination in a clip having a back portion and a front portion completely encircling the edge of the turned back corner, said front portion being cut at an angle to coincide with the edges of the shingle, said back portion projecting from both sides of said shingle, being of greater length than the width of the shingle at the encircled edge of the turned back corner, and said back portion having struck out tongues engageable in apertures of said front portion, said tongues being of sufficient length to be forced downward against the said clip. 30

In testimony whereof I have affixed my signature.

CHAS. O'DELL.
